(Cl. D45—4)

Fig. 1.

Fig. 2.

Fig. 3.

Fig. 4.

Fig. 5.

Fig. 6.

Fig. 1 is a top plan view of the expandable link chain in contracted condition, showing my new design;

Fig. 2 is a top plan view thereof in partially expanded condition, portions of the conventional connecting links being visible between the main links and shown in broken lines;

Fig. 3 is a top plan view, on an enlarged scale, of one of the main links of the chain of Fig. 1;

Fig. 4 is an end elevational view of the link of Fig. 3 taken from the lower end of that figure;

Fig. 5 is an end elevational view of the link of Fig. 3 taken from the upper end of that figure; and

Fig. 6 is a side elevational view of the link of Fig. 3.

I claim:

The ornamental design for an expandable link chain for a bracelet or the like, as shown.
